UNITED STATES PATENT OFFICE

2,461,826

GOLF SWING TRAINER

Louis Martin Krautter, Glencoe, Ill.

Application October 9, 1946, Serial No. 702,153

4 Claims. (Cl. 273—35)

1

The invention relates to devices designed to coordinate and direct the mind and muscle of a player to overcome faults and distracting attentions to nonessential details, but more particularly to provide mechanical means whereby a student taking up the game of golf may learn from the properly adjusted apparatus whether he is in position to properly address the ball and whether he has assumed the proper and most efficient stance. With these general objects in view it is the primary object of this invention to provide a training device of this character which will be simple of construction, economical to manufacture and highly efficient in use.

Other objects will appear hereinafter.

The invention consists in the combinations and arrangements of parts hereinafter described and claimed.

The invention, its combinations and arrangements of parts will be better understood by reference to the accompanying drawings forming a part of this specification, and in which

Figure 1 is a fanciful front view of a student in stance and addressing the ball, guided by the apparatus embodying the invention;

Figure 2 is an enlarged view of the necessary parts of the apparatus shown in use in Figure 1;

Figure 3 is a section taken on line 3—3 of Figure 2;

Figure 4 is a bottom face view taken on line 4—4 of Figure 3, showing the steel plate carried by the ball; and

Figure 5 is a modified form of tee illustrating the novel method for holding the ball thereon.

The embodiment of the invention illustrated in the drawings comprises a small hollow rubber ball 11 attached to one end of a sight cord 12, by a conventional knot adjacent its end inserted through a small hole in the hollow ball, and at the other end of which is attached a mouth piece 14. Said mouth piece 14 is of integral construction preferably of a suitable plastic, having a body 13 with an outwardly tapering portion 15, rectangular in cross section, and provided with a marginal flange 16 and a peripheral flange 17 in parallel position and spaced therefrom, forming a peripheral recess 18. A mouth grip 19 projects outwardly from the flange 17 having a thin flat neck 20 terminating in bulb shaped part 21 substantially elliptical in cross section. The outer tapering portion 15 is provided with a tubular hole 22 through the median line of the portion 15, terminating in a longitudinal slot 23 communicating with a notch 24 in the flange 17. The sight cord is passed through the tubular

2

hole 22, passed rearwardly through the notch 24 and wound around the portion 15 in the peripheral recess 18, and its free end tucked under one or more of the windings, as shown in Figure 2. By this arrangement the sight cord may be properly adjusted as to length.

The ball 11 is equipped with a small steel disc 25 fastened thereto by suitable rivets 26. It is to be noted that the steel disc 25 and the sight cord 12 are at less than half circumferential distance apart, by which arrangement the sight cord 11 is brought to approximately the correct sight line when the student is in proper stance. To hold the sight cord sufficiently taut and to overcome the pull of the sight cord a special tee 27 is used which is equipped with a permanently magnetized block 28 mounted in the head of the tee 29. By this arrangement the ball with the steel disc 25 is held in place until the ball is hit by the student.

A modification of the ball and tee shown in Figures 2, 3, and 4 is illustrated in Figure 5, and comprises a golf tee 30 having a head 31 with a stud 33 projecting upwardly from the face thereof, and adapted to be inserted through a hole in the ball 32. By this arrangement a serviceable adaptation is provided which will serve equally well as releasable means for holding the ball 32 and sight cord 12 in alignment.

In use the device serves to train the user to keep his head still and pivot correctly when addressing and hitting the ball. The ball used must be light in weight so that when hit will sail around the user's head harmlessly.

While I have illustrated and described the preferred form of construction for carrying the invention into effect, this is capable of variation and modification without departing from the spirit of the invention. I therefore do not wish to be limited by the precise details disclosed, but desire to avail myself of such variations and modifications as fall within the scope of the appended claims.

I claim:

1. A golf swing trainer comprising a captive ball attached to a suitable cord; means for releasably holding said ball on the top of a tee; a mouth grip adapted to be held between the teeth of a player; and means for attaching said cord to said mouth grip.

2. The construction specified in claim 1 in which the said mouth grip is adjustably connected to said cord.

3. The construction specified in claim 1 in which the means for releasably holding a ball

on the top of the tee comprises an upwardly extending stud projecting through a hole in said ball.

4. A mouth grip for a captive ball comprising a body of plastic material having a bit portion adapted to be held between the teeth of the user; a recess externally of said body and outwardly of said bit portion adapted to receive wrappings of a cord having a captive ball on its free end; there being a duct extending longitudinally through the outer end of said body, a lateral opening outwardly at the inner end of said duct and an outwardly opening slot connected with said lateral.

LOUIS MARTIN KRAUTTER. 15
